MEANS FOR BREAKING THE FOUR SCORED CORNERS OF COLLAPSIBLE PAPER BOXES

George Seifert, Beverly Hills Township, Los Angeles County, Calif.

Application December 6, 1939, Serial No. 307,855

11 Claims. (Cl. 93—49)

This invention relates to paper box score-breaking machinery.

Paper boxes, which are ordinarily folded and collapsed by machinery for transportation and storage, when manually uncollapsed and set up by operatives into position for use, frequently fold outwardly at their corners, which causes considerable inconvenience and delay in folding said corners inwardly properly before said boxes are suitable for use.

The general object of this invention is to provide a machine for breaking the corner scores of such paper boxes before they are folded and collapsed by other suitable machinery, so that the four corners of said boxes will always fold inwardly properly, when said boxes are uncollapsed and set up by operatives into position for use.

With the above and other objects in view the invention consists in the novel and useful provision, formation, construction, association, and relative arrangement of parts, members and features, all as shown in a certain embodiment in the annexed drawings forming a part of this specification, in which the invention is described generally and more particularly pointed out in the claims.

In the drawings,

Fig. 1 is a side elevation of a portion of the gear side of my invention extending from the feed end of the machine.

Fig. 2 is a side elevation of the remaining portion of the gear side of my invention extending to the folding end of the machine.

Fig. 3 is a plan view of the portion of my invention shown in Fig. 1.

Fig. 4 is a plan view of the portion of my invention shown in Fig. 2.

Fig. 5 is a side elevation of the box folding mechanism taken on line 5—5 of Fig. 4, shown in position at the beginning of its folding operation.

Fig. 6 is a fragmentary side elevation of the box folding mechanism taken on line 5—5 of Fig. 4, shown in position at the end of its folding operation.

Fig. 7 is a transverse vertical section taken on line 7—7 of Fig. 5.

Fig. 8 is a transverse vertical section taken on line 8—8 of Fig. 1.

Fig. 9 is a transverse vertical section taken on line 9—9 of Fig. 1.

Fig. 10 is a transverse vertical section taken on line 10—10 of Fig. 5.

Fig. 11 is a transverse vertical section taken on line 11—11 of Fig. 2.

Fig. 12 is an end view of the clutch and sprocket for the feed chain.

Fig. 13 is a transverse vertical section taken on line 13—13 of Fig. 12.

Fig. 14 is a plan view of a blank from which the box is made.

Fig. 15 is a plan view of a box blank showing the first fold.

Fig. 16 is an end view of Fig. 15.

Fig. 17 is a plan view of a box blank showing the first and second folds.

Fig. 18 is an end view of Fig. 17.

Fig. 19 is a plan view of a box blank as it leaves the machine.

Fig. 20 is a transverse vertical section taken on line 20—20 of Fig. 3, illustrating the securing means for the adjustable edge guide bars of the feeding means for the box blanks.

Fig. 21 is a transverse vertical section taken on line 21—21 of Fig. 4.

Fig. 22 is a transverse vertical section taken on line 22—22 of Fig. 5.

Referring more particularly to the drawings, in which corresponding parts are designated by the same reference characters in all of the figures, I designates a frame, upon which the various mechanisms and parts of my invention are mounted, which frame includes a pair of spaced side members 2, a plurality of connecting bars 3, a connecting bar 4, and a pair of connecting rods 5, which bars and rods are connected at their ends respectively to said side members, the bars 3 connecting the lower portions of said side frame members and the bar 4 and rods 5 connecting the upper portions of said side frame members.

On the frame I are mounted a feeding mechanism 8, for feeding the paper boxes, and a folding means 9 for preliminarily folding the paper boxes in the manner and for the purpose hereinabove more fully described.

The feeding mechanism 8 includes generally a feed table 10; a rotary feed roller 11; a pair of feed chains 12, and sprockets 13 and 14 and tightening idlers 15 over which said chains extend; guide plates 16 over which the paper boxes are fed by the chains 12; edge guide bars 17 for the boxes; and guide rods 18 under which the boxes are fed by the chains 12. The feed table 10 is pivoted at its forward end to the feed end of the machine on a pivot rod 19, which is secured in the side members 2 of the frame I and extends through webs 20 formed on the under side of said feed table. Pawls 21 are pivoted to the webs 20 of the feed table 10 and

engage ratchets 22 on the adjacent ends of the frame side members 2, for holding the feed table at different inclinations to which it may be adjusted on its pivot 19, extending downwardly in a forward direction to the rear ends of the feed chains 12. The rotary feed roller 11 is secured on a shaft 23 extending transversely of the machine with its ends journaled in bearings 24 upstanding from the side members 2 of the frame 1, the feed roller 11 being so positioned on the shaft 23 that the lower portion of its periphery lies adjacent the lower forward end of the feed table 10 and immediately above and between the box-receiving ends of the chains 12 to enable the feeding wheel 11 to feed the unfolded paper boxes 25 from the feed table 10 onto the adjacent box-receiving ends of said feed chains 12, there being a rubber friction plate 26 secured on the periphery of the feed roller 11 for engaging the uppermost paper boxes 25 on the feed table 10 and feeding said boxes successively, each revolution of said feed roller from said feed table to the box receiving ends of the chains 12, as aforesaid. The sprockets 13 are secured in suitably spaced relation on a shaft 27, which extends transversely of the frame 1 directly below the feeding wheel shaft 23, and said shaft 27 is journaled at its ends respectively in the side frame members 2. The sprockets 14 are secured in the same spaced relation as the sprockets 13 on a shaft 28, which extends transversely of the frame 1 and is journaled at its ends respectively in the side frame members 2. The chains 12 are spaced by the sprockets 13 and 14 in such relation as to support the paper boxes 25 for feeding the same from the feed table 10 to the box-folding mechanism. The tightening idlers 15 are journaled on the lower ends of a pair of arms 29, the upper ends of which arms are turnably mounted on a shaft 30 which extends transversely of the frame 1 and is secured at its ends in the side frame members 2, the idlers 15 engaging the lower reaches of the chains 12, under the weight of said idlers and arms 29, for drawing the upper reaches of said chains taut into a horizontal position for feeding the boxes 25. On the chains 12 are secured, in suitably spaced relation, a plurality of pins 31 for engaging the rear edges of the paper boxes 25 for feeding said boxes from the feed table 10 to the folding mechanism 9. The guide plates 16 are mounted at the outer sides of chains 12, respectively, near their ends on the upper ends of vertical supporting arms 32 which arms are formed on their lower ends with sleeves 32' slidably fitted on rods 33 extending transversely of the frame 1 and secured at their ends in the side members 2 of said frame. Set screws 34 are threaded in the sleeves 32' of arms 32 for engaging the rods 33 for securing said arms in different positions along said rods, whereby the guide plates 16 are secured in their proper laterally adjusted positions with relation to the chains 12, with the inner edges of said plates spaced slightly outwardly of said chains so that said chains may travel freely along said edges of said guide plates without engaging said edges. The edge guide bars 17 are mounted for lateral adjustment upon the guide plates 16 by means of clamp bolts 35 and thumb nuts 36, which bolts extend upwardly through transverse slots 37 in said guide plates and through said guide bars, and which nuts are threaded on the upper ends of said bolts for engagement with the upper side of said guide bars for drawing

the heads 38 of said clamp bolts 35 against the lower side of said guide plates 16, whereby said guide bars 17 are secured in laterally adjusted positions for guiding paper boxes 25 of different widths. The guide bars 17 are formed with inwardly extending guide flanges 39 under which the edges of the boxes 25 pass when fed by the chains 12 whereby said edges of said boxes are prevented from swinging upwardly out of feeding position. The guide rods 18 extend above and near the outer sides of the chains 12 and are formed at their rear ends with upwardly extending members 40 and at their forward ends with upwardly extending members 41, which members 40 and 41 extend through sleeves 42 and 43 respectively, the sleeves 42 being secured on a rod 44 extending transversely of the frame 1 and secured at its ends in the frame side members 2, and the sleeves 43 being secured on the frame connecting bar 4, and said members 40 and 41 are adjustably secured in said sleeves 42 and 43, respectively, by set screws 45 and 46 threaded in said sleeves, respectively, whereby the guide rods 18 may be adjusted as to height with relation to the chains 12, so that the boxes 25 fed by said chains will pass under said guide bars and be prevented by said guide bars from buckling upwardly and escaping the pins 30 on the chains 12.

The folding means 9 includes a side folding mechanism 50 and an end folding mechanism 51. Said side folding mechanism includes a pair of lower endless conveyor belts 52, a pair of upper endless conveyor belts 53, a pair of lower belt guides 54, a pair of upper belt guides 55, a pair of side folding bars 56 and a pair of top folding rods 57. Each of the belts 52 extends over pulleys 58 and 59 secured on shafts 60 and 61, respectively, which shafts extend transversely of the frame 1 and are journaled at their ends in the frame side members 2. The pulleys 58 and 59 are secured short distances apart on their shafts 60 and 61, respectively, whereby the belts 52 are spaced sufficiently close together to extend between the side folding bars 56, which are spaced apart the width of the folded boxes 25. Each of the belts 53 extends over pulleys 62 and 63 secured on shafts 64 and 65 respectively, which shafts extend transversely of the frame 1 and are journaled at their ends in the frame side members 2 above the shafts 60 and 61 respectively. The pulleys 62 and 63 are secured short distances apart on their shafts 64 and 65, respectively, whereby the belts 53 are spaced sufficiently close together to extend between the side folding bars 56. The upper reaches of the belts 52 extend over and along the upper edges of the guide bars 54, which are mounted on the upper ends of legs 66, the lower ends 67 of which are slidably fitted on rods 68 extending transversely of the frame 1 and secured at their ends in the side frame members 2. Set screws 69 are threaded in the lower ends 67 of the legs 66 for engaging the rods 68 for securing said legs and the guide bars 56 in the positions to which they are adjusted with said guide bars resting directly under the upper reaches of the belts 52 respectively. The lower reaches of the belts 53 extend over and along the lower edges of the guide bars 55, respectively, which are mounted on the frame 1 by means of standards 70 supported on the side frame members 2, a shaft 71 secured at its ends in the upper ends of said standards and extending transversely of the frame 1, horizontal arms 72 se-

cured on said shaft 71, and vertical arms 73 upstanding from said guide bars 55 and connected at their upper ends to the ends of said horizontal arms 72. A pair of bell-crank levers 74 are mounted on the shaft 71 with rollers 75 and 76 journaled on the ends, respectively, of each of said bell-crank levers, and said bell-crank levers are positioned on said shaft 71 so that the belts 53 extend under the rollers 75 respectively and over the rollers 76 respectively. Set screws 77 are threaded in the hubs of the bell-crank levers 74 to be tightened against the shaft 71 for securing said bell-crank levers in adjusted position with their rollers 75 and 76 engaging opposite sides of the belt 53 and taking up the stretch in said belt. The side folding bars 56 are mounted on the upper ends of legs 78, which are formed at their lower ends with sleeves 79 slidably fitted on the rods 68, and set screws 80 are threaded in said sleeve to be tightened against said rods for securing said side folding bars in their proper laterally adjusted position. The side folding bars 56 are formed with inclined cam folding surfaces 81 extending forwardly from the rear ends of said bars, which surfaces are engaged by the sides of the boxes 25, when fed forwardly between said bars by the belts 52 and 53, whereby the sides of the boxes are folded upwardly. The top folding rods 57 extend from the remote ends of the chains 12 forwardly over the side folding bars 56 and through the end folding mechanism 51, and said rods are formed with upstanding extensions 82 and 83, the extensions 82 extending through sleeves 84 secured on the transverse connecting bar 7, and the extensions 83 extending through sleeves 85 secured on a transverse connecting bar 86, which extends transversely of the frame 1 and is secured at its ends to the side frame members 2, there being set screws 87 and 88 threaded in the sleeves 84 and 85 respectively which are tightened against said extensions 82 and 83 respectively for securing the top folding rods 57 adjusted to the proper elevation, with the rear ends of said rods slightly above the remote ends of the chains 12 and said rods extending upwardly forwardly at 89 at an inclination over the inclined cam folding surfaces 81 of the side folding bars 56 and forwardly horizontally at 90 directly over the upper horizontal top folding surfaces 91 of said side folding bars, so that the paper box blank will pass from the remote ends of the chains 12 under the rear ends of said top folding rods 57 and between the belts 52 and 53 forwardly between the inclined folding surfaces 81 and the inclined portions 89 of said rods 57 and then forwardly between said rods and the horizontal top surfaces 91 of said side folding bars.

The end folding mechanism 51 for the boxes 25 includes generally an endless conveyor chain 92, a pair of side guide and holding rods 93, the forward portions of the top folding rods 57, an end forming block 94, a pair of end folders 95 and 96, a pair of rack bars 97 and 98 for operating said folding block and said end folders respectively, a pair of pinions 99 and 100 for engaging a pair of endless racks 101 and 102 respectively in rack bar 97, for actuating said rack bar, a pair of pinions 103 and 104 for engaging a pair of endless racks 105 and 106 respectively in rack bar 98, for actuating said rack bar, and a pair of cams 107 and 108 for swinging the end folders 95 and 96 respectively into folding position for folding the ends of the boxes 25.

The conveyor chain 92 extends over four sprockets 109, 110, 111 and 112, on shafts 113, 114, 115 and 116 respectively, which shafts extend transversely of the frame 1 and are journaled at their ends in the side frame members 2. The sprocket shaft 113 is located immediately forwardly of the shaft 61, on which are secured the pulleys 59 for the belts 52, and said sprocket shaft, and sprocket shaft 114 are so positioned that the upper reach of the chain 92 extends horizontally in alignment with and forwardly of the upper reach of the belt 52 and lower reach of belt 53, so that the boxes 25 with their sides folded will pass from between the forward ends of said reaches of said belts 52 and 53 onto the rear end of said upper reach of chain 92. Lugs 117 are secured on the outer edge of the chain 92 in suitable spaced relation to engage the rear edge of the boxes successively on said chain, so that said boxes will be properly fed by said chain through the end folding mechanism 51. The sprocket shafts 115 and 116 are located below the sprocket shafts 114 and 113 respectively.

The side guide and holding rods 93 extend forwardly horizontally and parallel from the upper inner corners of the side folding bars 56 through the end folding mechanism 51 to the inner ends of a pair of bars 118 extending inwardly from the side frame members 2 respectively, the rear ends of said guide and holding rods 93 being secured to the forward ends of said side folding bars 56, respectively, and the forward ends of said rods being secured to the inner ends of said bars 118, respectively, at the upper surface of said bars.

A pair of cleats 119 are secured to the upper side of the end forming block 94 by screws 120 and said cleats extend upwardly between a pair of flanges 121 depending from the lower edge of the upper rack bar 97, to which flanges said cleats are secured by bolts 122, whereby the end forming block 94 is secured to said rack bar 97, there being a plurality of spaced bolt holes 123 in said flanges 121 to receive the bolts 122 for securing the end forming block 94 in different positions along the lower edge of the rack bar 97 for adjustment of said block to the end folders 95 and 96.

The end folder 95 includes a rock shaft 124, a pair of rear end folding members 125 secured on said shaft, and a cam-engaging arm 126 secured on one end of said shaft for engaging the cam 107, said shaft 124 being journaled in bearings 127 on the outer ends of arms 128 outstanding from the sides, respectively, of a block 129, which is secured on the upper edge of the rack bar 98 near the rear end of said rack bar, between a pair of flanges 130 upstanding from said upper edge of said rack bar, by bolts 131 extending through said flanges and the lower portion of said block. The cam 107 is supported on a stud 132 extending inwardly from one of the side frame members 2. In the upper face of the block 129 is provided a groove 133 to receive the chain 92 to enable the lower rack bar 98 to be moved upwardly far enough to bring the upper face of said block 129 up adjacent the lower face of the end folding form block 94, when the upper rack bar 97 is moved down to its lowermost position with said lower face of said form block adjacent the upper edge of the chain 92.

The end folder 96 includes a rock shaft 134, a pair of forward end folding members 135 secured on said shaft, and a cam-engaging arm 136 secured on one end of said shaft for engaging

the cam 108, said shaft 134 being journaled in bearings 137 on the outer ends of a pair of arms 138 outstanding from the sides, respectively, of a block 139 secured in the upper edge of the rack bar 98, forwardly of the block 129, between the flanges 130, by bolts 140 extending through said flanges and the lower portion of said block 139. The flanges 130 are provided with a plurality of longitudinally spaced bolt holes 141 to receive the bolts 140 for securing the block 139 in different positions along the upper edge of the rack bar 98 for adjustment of the forward end folder 96 to the forward end of the end-folding form block 94. The block 139 is provided with a groove 142 in its upper face to receive the chain 92 to enable the lower rack bar 98 to be moved upwardly far enough to bring said upper face of said block 139 up adjacent the lower face of the end folding form block 94, when the upper rack bar 97 is moved down to its lowermost position with said lower face of said form block adjacent the upper edge of the chain 92. A pair of adjustable box gauges 143, each comprising a gauge plate 144 formed with a base plate 145 provided with a slot 146, are adjustably mounted on the sides respectively of the block 139, by means of screws 147, which extend through the slots 146 in the base plates 145 into threaded openings 148 in the sides respectively of said block 135, and secure said base plates 145 against the sides respectively of said block 139, with the upper ends of said gauge plates extending above the chain 92 at the sides respectively of said chain for engaging the forward edge of each box 25, while the rear edge of said box is engaged by one of the lugs 117 on said chain, whereby the box blanks 25 are positioned centrally under the end-folding form block 94, so that the ends of the box may be accurately folded upwardly by the end folders 95 and 96. The block 139 is provided in its sides with a number of said threaded openings 148, any two of which in each side of said block may be selected to receive the screws 147 for securing the box gauges 143 in different positions along the sides of said block, whereby the gauges may be adjusted to a greater extent, than by means of the slots 146, for centering box blanks 25 of boxes of different sizes as to length. The cam 108 is secured on the inner end of a threaded stud 149, the outer end of which extends through a horizontal slot 150 in one of the side frame members 2 and said stud is secured in said frame member at different positions in said slot by a pair of nuts 151 and 152, threaded on said studs, and a pair of washers 153 and 154 on said stud, which nuts clamp said washers respectively against the inner side and outer side of said frame member, whereby the cam 108 is adjustably secured in different positions to engage and operate the forward end folder 96 for boxes of different lengths.

The endless racks 101 and 102 are each formed with two straight sides extending longitudinally of the rack bar 97, and said rack bar is formed with two pinion guides 155 and 156 extending within said endless racks 101 and 102, respectively, around which guides roll the hubs 157 and 158 of the pinions 99 and 100 respectively, as said pinions are rotated, whereby said pinions are guided in mesh with said racks respectively. The pinions 99 and 100 are secured on shafts 159 and 160, respectively, which shafts are journaled in bearings 161 and 162, respectively, extending inwardly from one of the side frame members 2.

- 1 The endless racks 105 and 106 are each formed with straight sides extending longitudinally of the rack bar 98, and said rack bar is formed with two pinion guides 163 and 164 extending within 5 said endless racks 105 and 106 respectively, around which guides roll the hubs 165 and 166 of the pinions 103 and 104, respectively, as said pinions are rotated, whereby said pinions are guided in mesh with said racks, respectively.
- 10 The pinions 103 and 104 are secured on shafts 167 and 168, respectively, which shafts are journaled in bearings 169 and 170, respectively, extending inwardly from one of the side frame members 2.
- 15 The sprockets 109, 111 and 112 are secured fast on the shafts 113, 115 and 116, respectively, while the sprocket 110 is yieldingly connected to the shaft 114 by means of a spring clutch 171, so that said sprockets and the chain 92 may travel 20 at a slower speed than the drive shaft 114 during the end folding operation of the box blanks 25, in the manner and for the purpose hereinafter more fully described. The spring clutch 171 comprises a clutch member 172 keyed on the drive shaft 114 by a key 173, a coil spring 174, a lug 175 on said clutch member and a lug 176 on the sprocket 110. The spring 174 is coiled within a socket 177 in the clutch member 172 around an extension 178 of the hub 179 of the sprocket 110, and one end 180 of said spring 174 is secured in said clutch member 172, while the other end 181 of said spring is secured in said sprocket 110 which is turnable on the shaft 114. A collar 182 is adjustably secured on the shaft 114 by a set screw 183 for engaging the outer end of the hub 179 of the sprocket 110 for properly positioning said sprocket on the shaft 114 adjacent the socket end of the clutch member 172.
- 25 The driving means 185 of my invention will now be described. On the outer side of one of the side frame members 2 a drive shaft 186 is journaled in bearings 187 secured on said side frame member, and on said drive shaft are secured a drive pulley 188 and bevel gears 189, 190, 191 and 192, which bevel gears mesh, respectively, with bevel gears 193, 194, 195 and 196 secured, respectively, on stud shafts 197, 198, 199 and 200 journaled on said side frame member. On the stud shaft 197 is also secured a pinion 201 in mesh with an idler pinion 202 journaled on said side frame member 2, which idler pinion meshes with an idler 203 loose on the sprocket shaft 27, and said idler 203 meshes with a gear 204 secured on the feed roller shaft 23. On the 30 stud shaft 198 is secured a pinion 205 in mesh with an idler pinion 206 journaled on side frame member 2, which idler pinion meshes with another idler pinion 207 also journaled on said side frame member, and said idler pinion 207 meshes with a pinion 208 and a gear 209 secured, respectively, on the sprocket shaft 28 and the belt pulley shaft 60, and said gear 209 meshes with a gear 210 secured on the belt pulley shaft 64. On the stud shaft 199 is secured a pinion 211 in mesh with an idler 212 journaled on said side frame member 2, which idler meshes with an idler 213, loose on the sprocket shaft 113, and with another idler 214 secured on a stud shaft 215 journaled on said side frame member. Said idler 213 meshes with a gear 216 secured on the belt pulley shaft 61 and said gear 216 in turn meshes with a gear 217 secured on the belt pulley shaft 65. A second idler 218 is secured on the idler shaft 215 in mesh with another idler 35
- 40
- 45

- 55
- 60
- 65
- 70

219 journaled on said side frame member 2, and said idler 219 in turn meshes with an idler gear 220 journaled on said side frame member, which idler gear meshes with two pinions 221 and 222 secured on the outer ends of the pinion shafts 167 and 168 respectively, and said idler gear also meshes with an idler gear 223 journaled on said side frame member, which idler gear 223 in turn meshes with two pinions 224 and 225 secured on the outer ends of the pinion shafts 159 and 160, respectively. On the stud shaft 200 is secured a pinion 226 in mesh with an idler 227 journaled in said side frame member 2, which idler in turn meshes with a gear 228 secured on the sprocket shaft 114.

The operation, uses and advantages of my invention are as follows:

A number of box blanks 25 are stacked upon the feed table 10 with the forward end 229 of the uppermost blank extending under the feed roller 11 and with the remaining blanks positioned progressively downward at short distances rearwardly of each other as shown in Fig. 3.

Power is applied through a belt (not shown) to the pulley 188 and said pulley, drive shaft 186 and bevel pinions 189, 190, 191 and 192 are rotated. The bevel pinion 193, stud shaft 197 and pinion 201 are rotated by said bevel pinion 189; the idler 202 is rotated by said pinion 201; the idler 203 is rotated by said idler 202; and the gear 204, feed-roller shaft 23 and feed roller 11 are rotated by said idler 203. The bevel pinion 194, stud shaft 198 and pinion 205 are rotated by the bevel gear 190; the idler 206 is rotated by said pinion 205; the idler 207 is rotated by said idler 206; and the pinion 208, sprocket shaft 28 and sprockets 14 are rotated by the idler 207, which sprockets drive the conveyor chains so that the upper reaches of said chains travel forwardly toward the folding mechanism 9, or to the right, as shown in Fig. 1.

As the feed roller 11 is rotated the rubber friction plate 26 on the periphery of said roller engages the forward end member 229 of the uppermost box blank 25 and feeds said blank forwardly onto the upper reaches of the chains 12, while the next box blank 25 slides downwardly and forwardly a short distance until its forward end member 229 rests under the feed roller 11 in position to be engaged by said friction plate 26 on the next revolution of said feed roller. The box blank 25, fed on the chains 12, as aforesaid, is engaged at the rear edge of its rear end member 230 by two pins 30 on said chains, respectively, and said blank is thereby fed forwardly by said chains, between the guide bars 17 under the guide flanges 39 of said bars and under the guide rods 18, until said blank is fed between the endless belts 52 and 53 of the side-folding mechanism 50. Said endless belts 52 and 53 are driven from the drive shaft 186 through the medium of bevel pinions 190 and 194, pinion 205, idlers 206 and 207, intermeshing gears 209 and 210 respectively, shafts 60 and 64 respectively and pulleys 58 and 62 respectively, and said endless belts 52 and 53 are also driven from the drive shaft 186 through the medium of bevel pinions 191 and 195, pinion 211, idler 212, idler 213, gears 216 and gear 217 respectively, shafts 61 and 65, respectively, and pulleys 59 and 63 respectively, so that the upper reach of belt 52 and the lower reach of belt 53 travel forwardly. Said box blank 25, fed by chains 12, between the adjacent reaches of the belts 52 and 53 is gripped by said belts between their adjacent reaches and fed

forwardly between the side folding bars 56 and the inner side flap bending rods 57, and the side walls 231 of said box blank are folded upwardly vertically by their engagement with the cam-folding surfaces 81 of said side folding bars 56, while the top members 232 of said box blanks are folded outwardly horizontally by the top folding rods 57 over the upper inner edges 233 of said side folding bars 56 respectively, as illustrated in Fig. 9 of the drawings. The folded condition of the box blank 25 as above described is further illustrated in Figs. 15 and 16.

Said box blank 25 with their side walls and top members folded, as above described, are fed further forwardly by the belts 52 and 53 onto the rear end of the upper reach of the chain 92 of the end folding mechanism 51. Said chain 92 is driven by the drive shaft 186, through the medium of bevel pinions 192 and 196, pinion 226, idler 227, gear 228, shaft 114 and sprocket 110, so that the upper reach of said chain 92 travels forwardly, or to the right, as shown in Fig. 2. One of the lugs 117 on said chain 92 engages the rear edge of the rear end wall 230 of the box blank 25 fed onto the rear end of the upper reach of said chain and said box blank is thereby fed forwardly by said chain between the blocks 129 and 139 and the form block 94, until the forward edge of the forward end wall 229 of said blank engages the gauge plate 144 of the gauge 143, whereby said box blank is centered with relation to said form block 94 and the end benders 95 and 96 for folding the end walls 229 and 230 of said box blank during which operation the lower rack bar 98 and blocks 129 and 139 have been moved upwardly, by the engagement of the pinions 165 and 166 with the right ends of the racks 105 and 106, respectively, until the upper faces of said blocks have engaged the lower side of said box blank 25 and the bottoms of the grooves 142 in the upper faces of said blocks engage the lower side of the upper reach of chain 92, and the upper rack bar 97 and form block 94 have been moved downwardly, by the engagement of the pinions 157 and 158 with the right ends of the racks 101 and 102, respectively, until the lower face of the form block 94 have engaged the upper side of said box blank and the lower side of said box blank engages the upper side of said chain 92, (Fig. 5) the pinions 165 and 166 being rotated from the drive shaft 186, through the medium of the bevel pinions 191 and 195, pinion 211, idlers 212, 214, 218 and 219, gear 220, pinions 221 and 222 and pinion shafts 167 and 168, respectively, and the pinions 157 and 158 being also driven by the drive shaft 186 through the medium of said bevel pinions 191 and 195, pinion 211, idlers 212, 214, 218 and 219 and gear 220, and through the gear 223, pinions 224 and 225 and pinion shafts 159 and 160, respectively. With the box blank 25 and the upper reach of chain 92 gripped between the blocks 129 and 139 and the block 94, said box blank and said chain are moved together forwardly by the rack bars 97 and 98, which rack bars are moved forwardly at a slower speed than the chain drive sprocket 110, by the engagement of the pinions 99 and 100 with the upper straight sides of the endless racks 101 and 102, respectively, of the rack bar 97, and by the engagement of the pinions 103 and 104 with the lower sides of the endless racks 105 and 106, respectively, of the rack bar 98, said slower forward movement of the chain 92 being permitted by the yielding and winding of the spring 174 of the spring clutch

171, so that the clutch member 172, which is keyed on the sprocket shaft 114 may run ahead of the sprocket 110 for a short distance. As the gripped box blank 25 is moved forwardly, as aforesaid, the cam arms 126 and 136 of the end folders 95 and 96, respectively, engage the cams 107 and 108, respectively, and actuate said end folders, so that their folding members 125 and 135 are swung upwardly in engagement with end walls 230 and 229, respectively, of the box blank 25, as illustrated in Fig. 6 of the drawings, until said walls are folded vertically against the adjacent rear and forward ends of the form block 94, and the rear corner members 234 and the forward corner members 235 of said box blank are folded outwardly upon themselves, as illustrated in Figs. 17 and 18, thus completely preliminarily folding the box blank in the reverse direction to which it is folded into its final form as a box, whereupon the cam arms 126 and 136 of the end folders 95 and 96 escape the cams 107 and 108 and said end folders swing down to their normal positions, swinging their folding members 125 and 135 down and away from the folded end walls 230 and 229 of the box 25, as illustrated in Fig. 5. The pinions 99 and 100 have now reached the rear ends of the upper reaches of the racks 101 and 102, respectively, and begin to travel downwardly around the rear arcuate ends of said racks, while the pinions 103 and 104 have reached the rear ends of the lower reaches of the racks 105 and 106, respectively, and begin to travel upwardly around the rear arcuate ends of said racks, whereupon the rack bar 97 and form block 94 are moved upwardly until said form block is lifted above the preliminary folded box form 25, while the rack bar 98, blocks 129 and 139 and the gauge member 144 are moved downwardly below said box blank and the chain 92, releasing said chain, so that the clutch spring 174 will wind and rotate the sprocket 110 forwardly, at a faster speed than the speed of the clutch member 172, until the lug 176 on said sprocket engages the lug 175 on said clutch member, whereupon the sprocket 110 is rotated and the chain 92 moved forwardly by the clutch member 172, through the clutch spring 174, at the same rate of speed as said clutch member and sprocket shaft 71, and said preliminary folded box 25 is again engaged at its rear end by said lug 117, which engages the folded rear end wall 230 of said box, and said box is conveyed forwardly by the chain 92 and said lug over the sprocket 110, and is delivered onto the table at the forward end of the machine, whereupon the folded parts of said box blank unfold downwardly until said parts and the bottom of the box blank are again flat, as shown in Fig. 19, but with the corner scores of the box blank broken, so that said blank may be more easily folded for use by operatives, in the reverse direction to which said parts of the box were preliminarily folded by the machine.

As the folded box blank 25 is moved forwardly by the chain 92 and its lug 117, as aforesaid, the pinions 99 and 100 have traveled downwardly around the rear arcuate ends of the racks 101 and 102, respectively, and said pinions then travel forwardly along the lower reaches of said racks, until the rack bar 97 is moved rearwardly to its initial uppermost position, while the pinions 103 and 104 have traveled upwardly around the rear arcuate ends of the racks 105 and 106, respectively, and said pinions then travel forwardly along the upper reaches of said racks,

until the rack bar 98 is moved rearwardly to its initial lowermost position, at which time the succeeding box blank 25 has been fed by the machine from the feed table 10, between the form block 94 and the blocks 129 and 139 into position to be folded in the same manner as the preceding folded box blank was fed between said blocks to be folded, thus completing a cycle of operations of the machine, which is repeated, so that the box blanks 25, stacked on the feed table 10, are successively fed, folded and delivered, as above described.

I claim:

1. A corner breaking machine as disclosed comprising means for bending the sides of the box blanks, and means for folding the ends of the box blanks and for folding the uncut corner areas of the box blanks outwardly on their diagonal scores.
2. A box-folding machine as disclosed comprising means for folding the sides of the boxes, means for feeding the box blanks to said side-folding means, means for folding the ends of the box blanks and for folding the uncut corner areas of said box blanks outwardly on their diagonal scores, and means for feeding said box blanks from said side-folding means to said end-and-corner-folding means.
3. A box-folding machine as claimed in claim 1 in which the sides, ends and uncut corner areas of the box blanks are folded in the reverse direction to which they are finally folded to form the boxes.
4. A box-folding machine as claimed in claim 2 in which the sides, ends and uncut corner areas of the box blanks are folded in the reverse direction to which they are finally folded to form the boxes.
5. In a box-folding machine as disclosed, a pair of rack bars arranged one above the other, continuous racks in said rack bars, pinions in mesh with said racks, blocks on the upper edge of said lower rack bar, a block on the lower edge of said upper rack bar, means for feeding the box blanks with their sides folded between the blocks on said lower rack bar and the block on said upper rack bar, so that each box blank will be gripped between said blocks when said rack bars are moved toward each other by their racks and pinions, end-and-corner folders, and means for operating said end-and-corner folders for folding the ends and corners of each box blank when gripped between the blocks on said lower rack bar and the block on said upper rack bar.
6. In a machine as disclosed, means for breaking outwardly on their diagonal scores the scored uncut corner areas of paper box blanks for folding said blanks into boxes.
7. In a machine as disclosed, means for breaking outwardly on their diagonal scores the scored uncut corner areas of paper box blanks in reverse direction prior to folding said blanks in the obverse direction to form boxes.
8. In a machine as disclosed, means for breaking outwardly on their diagonal scores the scored uncut corner areas of the blanks of collapsible paper boxes, in reverse direction, before said blanks are folded into boxes and said boxes are collapsed.
9. The method of causing the uncut corner areas of collapsible set-up boxes to fold inwardly when said boxes are collapsed and set up, which consists in breaking outwardly on their diagonal scores the scored uncut corner areas of the box

blanks before said blanks are folded into boxes.

10. The method of causing the uncut corner areas of collapsible set-up boxes to fold inwardly when said boxes are collapsed and set up, which consists in breaking outwardly on their diagonal scores the scored uncut corner areas of the box blanks in the reverse direction before said blanks

are folded in the obverse direction into boxes.

11. In a machine as disclosed, means for breaking outwardly on their diagonal scores the scored uncut corner areas of the blanks of collapsible paper boxes before said blanks are folded into boxes and said boxes are collapsed.

GEORGE SEIFERT.
